UNITED STATES PATENT OFFICE

LEE H. MILLER, OF CLEVELAND HEIGHTS, OHIO

BUILDING CONSTRUCTION

Original application filed January 21, 1929, Serial No. 333,812. Divided and this application filed September 5, 1929. Serial No. 390,594.

This invention relates to ceiling means for floor structures of the class thereof including flanged structural steel beams, and more particularly the invention comprises blocks 5 adapted to interlock with the beam flanges and with each other, whereby substantially continuous ceiling is had.

This application is a division of my co-pending application, Serial No. 333,812, filed 10 January 21, 1929; in which copending application is shown and more fully described a floor construction wherein steel plates are supported by spaced structural steel beams of I section. In such construction it is important that the steel work be protected 15 against fire, which protection necessarily must be provided from beneath the floor, and logically by ceiling means extending generally along the bottoms of the floor beams, and 20 which may thus form air spaces beneath the floor plates and between the beams and at the same time present a nice appearance from beneath the floor.

The object of this invention is to provide 25 such a ceiling means of the utmost simplicity of design so that the same may be cheaply manufactured and even more cheaply installed, and yet the installation accomplish its purpose in a manner at least as satisfactory as by any means heretofore employed.

The exact nature of the invention together 30 with further objects and advantages thereof will be apparent from the following description taken in connection with the accompanying drawings in which Fig. 1 is a sectional elevation showing details of a complete floor including an application of my invention; Fig. 2 is a similar detail showing the manner in which the assembly of my ceiling blocks 35 is made in the construction of the floor; Fig. 3 is a section as in the plane of line 3—3, Fig. 1, and also indicates by line 1—1 the plane of the section of Fig. 1; and Fig. 4 is a perspective view of details of another generally 40 similar floor construction.

With reference now to the drawings and more particularly to the construction indicated Figs. 1-3, the main girders are indicated at 1. They are in the form of I beams 45 extending from column to column along the

walls, so that the main frame of the building, including all columns and these girders, can be erected or assembled by riveting or other operations in the customary manner. The spaces between opposite girders are bridged 55 or spanned by junior or subsidiary beams 2, preferably of I section as indicated.

In the form shown in the figures these beams are placed on top of the girders 1 and may extend continuously across the same or 60 terminate at the girders according to the lengths of the span. Upon the beams 2 are laid a series of steel plates 3, which are of proper width according to the spacing between beams so that the plates may be welded 65 to each other and to the beams to form a substantially integral structure. The top of the floor may be nicely finished off in the usual manner by a layer of surfacing 4 such as of cement.

According to my invention I take advantage of the lower flanges of the beams 2 for attaching my novel form of ceiling means. This ceiling means is preferably of fire proof material such as gypsum or like lithic product, and as has already been stated is in the 75 form of blocks adapted to interlock with each other and with the beam flanges.

With reference now to Figs. 1 and 2 each block is designated generally by the reference character 5 and comprises three principal parts. On one end of the typical block shown in Fig. 2 is a hook member 6 formed with its return bend above the intermediate or stretcher portion 7 of the block, and forming a notch 8 adapted to receive the flange 9 of the beam 2. Upon the opposite end of the block is a lip member 10 outwardly extending and spaced somewhat from the plane of the intermediate block portion 7 having an upstanding connecting portion 11 for the purpose. The proportions of the lip member and of its connecting portion 11 are such that the lip member 10 may overlie the 90 hook member 6 of an adjacent block—which has its hook member 6 engaging the flange 9 of beam 2, as indicated Fig. 1—to support its end of its block with the lower faces 12 95 of the adjacent blocks in the same plane. 100

The faces 12 of the blocks are flat and may be finished to present a neat appearance.

- The longitudinal dimensions of the blocks are immaterial and may be substantially as great as those of the beams 2 as indicated Fig. 4; while the transverse dimensions of the blocks will be evidently dependent upon the spacing of the beams with which the blocks are to be used. The proportions are such that the blocks may be assembled successively from left to right Figs. 1 and 2, each block being added to the assembly in the manner indicated Fig. 2 by inserting its lip portion 10 above the hook portion 6 of the last assembled block, swinging its hook portion 6 upward to the limit of the adjacent beam 2 and sliding the block to the left Figs. 1 and 2, to engage its hook portion with the beam flange 9. As indicated the proportions of the lower portions of the blocks and particularly the faces 12 are such that when the assembly is made as described the lower block surfaces will combine to form a substantially uninterrupted ceiling. If the faces 12 of the blocks are finished, therefore, the ceiling thus formed may present a satisfactory appearance although a finishing coat 13 of plaster may be added if desired. It will be noted that the joint between blocks includes vertical as well as horizontal stretches so that if the blocks are accurately made a very effective heat-resistant seal is had.

- The first block 5a in the assembly has no lip portion, and may be embedded in the concrete of the wall 14 as indicated Fig. 1, or may obviously be cut short thereof and its cut-off end be supported by other means. At the other end of the ceiling it is necessary to provide only means for supporting the far end of the last block and means for preventing movement of the blocks to the right Fig. 1. This may be accomplished by any convenient arrangement such as that indicated Fig. 3 wherein hollow tiles 15 arranged to fit within the channels of the girders 1 are shown as forming supporting means as well as abutments against longitudinal motion of the blocks.

- In the showing of Fig. 4 is indicated a wall of brick construction in place of the concrete indicated in Fig. 1. As to the floor itself, however, Fig. 4 merely makes more clear what has already been described. It will be noted Figs. 1 and 4 that when the assembly is complete the typical joint between blocks comes to one side of the floor beam and includes a bend having vertical and horizontal portions. Thus heat penetrating the ceiling by following the joint could reach the beam only by tortuous path. It will also be noticed that that side of the beam on which the corresponding joint is located is protected by the relatively large mass of ceiling material which comprises the hook and lip por-

tions of the corresponding blocks; whereas the opposite side of the beam is protected by a long integral block stretch, entirely unbroken by any joint. In fact, for each beam one flange is substantially surrounded by the fire-proof block material whereas the other flange is remote from the nearest ceiling joint. 70

What I claim is:

1. Ceiling means for floor structures of the class thereof including spaced flanged beams, said ceiling means comprising a block for engagement between a pair of said beams to form a ceiling therebetween, and having on one side a return bend hook member adapted to engage the far flange of one of said beams, and having on its opposite side an outstanding lip member adapted to rest upon the hook member of a similar block engaging the near flange of the other beam. 75

2. Ceiling means for floor structures of the class including spaced structural steel beams each beam having a flange, said ceiling means comprising interlocking blocks each having a hook portion engaging the flange of one beam and a lip portion overlying the hook portion of the next block, and each block having an intermediate ceiling portion extending immediately beneath the corresponding beam. 80

3. Ceiling means for floor structures of the class thereof including parallel beams flanged in the same direction, said ceiling means comprising a block for arrangement between a pair of beams and having at one edge a return-bend hook member adapted to engage the corresponding beam by the flange thereof extending away from said block, and having at the opposite edge a lip member adapted to overlie the hook member of a similar block engaging the second beam by the flange thereof extending toward said first named block. 85

In testimony whereof I hereby affix my signature.

LEE H. MILLER.
